UNITED STATES PATENT OFFICE

2,650,966

ELECTRICAL CONTACTOR

Paul V. Yingst, Norwood, Ohio, assignor to The Post-Glover Electric Company, Cincinnati, Ohio, a corporation

Application March 7, 1949, Serial No. 79,997

8 Claims. (Cl. 200—98)

1

This invention relates to improvements in electrical contactors and electrical systems.

The primary object of this invention is the provision of a direct current accelerating contactor of the single or double pole type embodying structural features set forth in U. S. Patent 2,632,822, dated March 24, 1953, more particularly directed to use as an accelerating contactor in connection with direct current motor control; the same being particularly well adapted for use in connection with the forward and reverse driving of a motor, and capable of supplying the control features of a reversing magnetic motor starter for either direction of rotation.

A further object of this invention is the provision of an improved accelerating contactor of the single or double pole type having associated therewith a shunt type holding coil for delaying energization of the motor for rotational change in direction, until the motor has reduced in speed so that the CEMF has reached a predetermined low percentage of rated voltage.

A further object of this invention is the provision of an improved accelerating contactor having associated therewith a main current controlling switch having electromagnetic operating means therefor including an armature, and a motor armature controlled holding coil associated in complementary relation with the armature of the switch, and further having associated therewith a normally closed auxiliary contact.

A further object of this invention is the provision of a contactor having the parts so constructed and arranged that the movable connection of all relatively movable parts is located close to the base panel for purposes more specifically enumerated in my Patent 2,632,822.

Other objects and advantages of this invention will be apparent from the following detailed description.

In the accompanying drawings, forming a part of this specification, and wherein similar reference characters designate corresponding parts throughout the several views—

Figure 1 is a plan view of the improved accelerating contactor, showing a double pole type.

Figure 2 is a side elevation of the contactor of Figure 1.

Figure 3 is a longitudinal cross sectional view taken thru the contactor substantially on the line 3—3 of Figure 1.

Figure 4 is an elevation of the double pole type contactor, taken from the holding coil end thereof.

2

Figure 5 is a cross sectional view taken substantially thru the double pole type contactor substantially on the line 5—5 of Figure 1.

Figure 6 is a cross sectional view taken thru the main switch controlling coil, holding coil and the common armature for said coils; the view being taken substantially on the line 6—6 of Figure 1.

Figure 7 is a plan view of a single pole type of accelerating contactor.

Figure 8 is a cross sectional view taken through the terminal structure of the normally closed auxiliary contact assembly, substantially on the line 8—8 of Figure 9.

Figure 9 is a plan view of a normally closed auxiliary contact associated with the accelerator contactor.

Figure 10 is a side elevation, partly in section, of the normally closed auxiliary contact assembly.

Figure 11 is a cross sectional view taken thru the contactor of Figure 7 substantially on the line 11—11 of Figure 7.

In the drawings, wherein for the purpose of illustration are shown single pole and double pole types of accelerating contactors, the letter A may generally designate the double pole accelerating contactor, and B the single pole accelerating contactor. They both embody similar constructions with the exception of the coil armature mounting.

In as far as applicable, similar reference characters designate corresponding parts thruout the various views of both forms of contactors.

Each of the accelerator contactors A and B includes a panel C having an improved contact arm structure D adapted for proper cooperation with a contact E with which is associated an arc extinguishing means F. An electromagnetic coil G is provided, with which is associated an armature H in the form of accelerating contactor A, and an armature H' in the form of accelerating contactor B.

With each of the forms A and B there is associated an improved holding coil structure K. Furthermore, there may be provided an auxiliary contact assemblage L, shown in detail in Figures 8, 9 and 10 of the drawings which may be made a part of and associated with the holding coil in either the double pole type of accelerating contactor or the single pole type of accelerating contactor.

The panel C is of a size and nature to conform to the capacity of the contactor and it may be provided with suitable apertures 10 for receiving mounting bolts. The base may be mount-

ed in vertical, horizontal or angular planes, as desired.

Referring to the contact arm construction D, the same preferably includes a cast aluminum rocker arm 15 of L-shaped formation. It comprises a lower contactor arm connecting portion 16 and a right-angled armature connecting portion 17. The arm 15 is provided with a barrel portion 18 adapted to receive from opposite sides thereof (Fig. 11) the reduced sleeve ends 20 of oil-less type of sleeve bearings.

A cast aluminum rocker arm support or bracket 21 is provided, having a base portion 22, bolted as at 23 to the panel C, as shown in Figure 3. This bracket 21 includes wall portions 24 and 25 extending normal to the plane of the panel C for supporting a mounting pin or shaft 25^a, as shown in Figure 11. The mounting pin 25^a has a head at one end and is secured by means of a cotter pin at its other end to the bracket structure, as shown. The flanged-type of oil-less bearing include, in addition to the sleeve portion 20, the outer enlarged flange portions 28 which abut the inner surface of the bracket supporting walls 24 and 25.

To the under surface of the rocker arm portion 16 is secured, by bolts 30, a beryllium-copper spring arm portion 35 of an inherent springy nature. With arm 35 is associated, as part of the contact arm, a laminated copper strip construction consisting of a plurality of copper strips 36. The parts 35 and 36 are connected to the rocker arm portion 16 by bolts or screws 30. At its end the contact arm is provided with a copper contact tip 40 which is silver inlaid. It covers the lower surface and the front edge of the arm and is provided with a screw threaded stud 41 which extends thru the end of the beryllium-copper spring arm portion 35 and is secured thereto by means of a nut 42. The laminations 36 are provided with kinks defining an expansion loop 50. The beryllium-copper portion 35 terminates at the mounting sleeve portion 18 of the rocker arm but the copper laminations continue around the portion 18 and extend upwardly for connection by means of a terminal bolt 52 to the rocker arm portion 17. This terminal bolt 52 also connects a conductor braid 53, the opposite end of which is connected to a binding post 54.

The copper contact E, which has a silver inlay tip, is mounted by means of a bolt 60 to the bight or base portion 61 of a U-shaped permanent magnet comprising part of the arc blowout F. The copper-silver contact E is provided with a face which slopes slightly towards the plane of the panel E, as will be noted from Figure 3, for efficient contact engagement with the contact tip 40 of the contact arm. A connecting link 62 is clamped between the contact E and the base 60 for conductor attachment with the binding post 64.

The U-shaped permanent magnet may be attached to the panel by means of screws, shown in dotted lines at 65 in Figure 1 of the drawings. It is to be noted that the surface engagement of contacts 40 and E lies within the permanent magnet.

An insulation and heat dissipating shield 70 is detachably connected with the upstanding walls or flanges 71 of the permanent magnet. It straddles the compartment wherein lie the contacts 40 and E and consists of a top wall 72, depending side walls 73 and a rear wall connecting lower portion 74. The walls are arranged to define a

compartment, shown at 76, which opens forwardly. The shield 70 has a passageway 77 for heat dissipation. The outer surfaces of the wall portion 77 are recessed for receiving the flanges 71 of the permanent magnet and the shield is provided with spring clip attaching arms 79 secured at 80 thereto, the lower ends of which are stud-notched to frictionally engage in recesses (not shown) located on the outer surfaces of the flanged portions 71 of the permanent magnet. It is obvious that the shield may be readily pulled upward and detached from the permanent magnet to expose the contacts.

For the double pole type of contactor, the above contact arm and complementary arc blowout are duplicated, as shown in Figures 1, 4 and 5 of the drawings. They are located in complementary relation and the rocker arm portions 17 thereof support an insulation plate or panel 90, secured as by screws 91 thereto. The terminal braid connecting bolt 52 also aids in securing the insulation plate 90 in position and the insulation panel is reinforced by a metal strip or plate 92 to which the screws or bolts 52 are also connected, as shown.

The electromagnet includes a coil G mounted upon an axis which is parallel with the plane of the panel C and as close as possible to the panel. Mounting is made upon the outstanding wall portion 100 of a yoke or bracket, the bottom or base 102 of which is attached by means of bolts 103 to the panel C. As is more clearly shown in Figure 6 of the drawings, the wall 100 of the yoke has attached thereto bolt 104 which extends into the core structure 105 of the coil. This efficiently mounts the coil in stable position upon the panel.

The armature H, of the double pole type of connector, is connected by the bolts 91, shown in Figures 1 and 4 to the reinforcing strip 92 and the insulation plate 90.

Each of the contact arms for the single and double pole-types of contactors includes an improved spring arrangement, best shown in Figures 1, 5 and 11 of the drawings which may appropriately be referred to as a double torsion type spring for the purpose of holding the contactor arm or arms open. These springs are centered on the pivot shafts of the respective contact arms. Each spring, designated at 110 in the drawings, includes a U-shaped portion the bight 111 of which engages the exposed face of the rocker arm portion 17 and thence extends downwardly at an acute angle to the plane of the contact arm and terminates in coil spring portions 113 wrapped around the flanged parts 28 of the rocker arm bearing structures. The normal effect of the springs 110 is to hold the contact arms open with respect to the contacts E, and of course to move the armature away from the core.

The armature structure H' for the single pole type of contactor switch shown in Figures 7 and 11, is provided with a sleeve portion 120 provided with a fixed pin 121, the ends of which seat in sleeve type oil-less bearings 122 mounted in ears or bearing lugs 123 which are integral with the coil mounting yoke base 102^a, shown in Figure 11.

The single and double pole accelerator contactors can be supplied with or without the arc blowouts above described.

Referring to the construction of the holding coil K, the armature structure H and H' of the forms of invention A and B above described also

serve as the armature for the holding or lockout magnetic path. The holding coil K is mounted upon a yoke 130 bolted as at 131 upon the panel structure C, as best shown in Figure 6. It has a holding circuit core 132 secured to the bracket or yoke 130 in an opening 134; a jamb nut 135 holding the adjustment. The holding coil K may be of either the series or shunt type, electrical connections being made thereto at the terminals 136. A thin nut and washer structure 137 secure the coil K in position upon the coil at the opposite end. It is quite apparent that the core 132 may be moved along its axis of the coil by loosening the nuts 135 and 137 for the purpose of varying the distance (air gap) between the armature end of the coil 132 and the armature plate 92. The axis of the coil K is slightly off parallel with the plane of the panel, so the armature of the switch will lie in a plane normal to the axis of the coil K when in attracted or held position.

It is intended that the auxiliary contact structure L be selectively utilized in connection with either the single pole or double pole type switches. The mounting is shown in Figures 8, 9, 10 and 11.

To that end the top wall of the yoke 130^a may serve as a support for the auxiliary terminals 140 and 141 which are in the form of angle clips secured to insulation blocks 142 and 143 respectively. The terminal pieces 140 and 141 are of copper or similar material and inlaid with silver on the contact surfaces thereof. The insulation mounting blocks 142 and 143 are secured to the bracket or yoke 130^a by screws or bolts 145 screw threaded into openings on the top wall of the bracket 130^a, as shown in Figure 10.

A thin layer of insulation material 146 insulates the contacts from the holding circuit yoke 130^a. Screws 148 mount the terminal pieces 140 and 141 in position, and the latter may be 40 supplemented with angle clips for supporting binding screws 149 and 150, as shown in Figure 8.

The movable part of the normally closed auxiliary contact assembly is mounted upon the main armature H or H', as the case may be. To that end, as shown in Figures 7, 9, 10 and 11, the armature H' is provided with a mounting opening 151 therein. A shorting bar 152 is provided, upon which contact points 152^a and 152^b are mounted for the contacts 140 and 141 above mentioned. The shorting bar 152 is provided with an opening thru which slidably extends a tube 154. A compression spring 155 is disposed between the armature H' and the shorting bar 152 for holding the latter in forward position. The entire structure is mounted upon a detachable bolt 156.

Inasmuch as the springs 110 normally throw the armature H and H' to open position with 60 respect to the electromagnetic coil G, it is quite obvious that the auxiliary contacts L are normally closed.

The accelerator contactor, merely by way of example, has a maximum capacity of 100 amperes per pole, 250 volts. Of course other sizes of similar construction can be made. They are adapted to operate on 80 to 110% rated voltage.

The improved accelerating contactors are used in connection with the forward and reverse drive 70 of an electric motor. The single pole contactor of the type shown in form B allows the use of a starting resistor, starting the motor with a limited inrush current, and progressive step by step cut-out of the resistor as motor current varies 75

between maximum and minimum as limited by the resistor. The minimum is determined by the adjustment of the core of the holding coil. A normally closed auxiliary contact in series with the shunt type holding coil is used only when full voltage would otherwise be applied to the holding coil during continuous operation. Since the holding coil of the contactor has no function during continuous operation, it need not be of the continuous type. Thus, the auxiliary contact is an added feature for such application, or for whatever purpose is found necessary.

Various changes in the shape, size and arrangement of parts may be made to the form of the invention herein shown and described without departing from the spirit of the invention or the scope of the following claims.

I claim:

1. In an accelerating contactor the combination of a supporting base, a main current controlling switch comprising a contact mounted upon the base and a contact arm pivoted upon the base on an axis substantially parallel to the base and close to the same, spring means normally throwing the contact arm to open position with respect to its contact, an armature pivoted upon the base on an axis common to the axis of the switch arm, said armature being connected to the switch arm for movement therewith, an electromagnetic coil mounted upon the base on an axis substantially parallel to and close to the base, and a holding coil for said armature mounted upon the base on an axis close to and non-perpendicular to the base and in armature attracting opposition with respect to the coil first mentioned.

2. In an accelerating contactor the combination of a supporting base, a main current controlling switch comprising a contact mounted upon the base and a contact arm pivoted upon the base on an axis parallel to the base and close to the same, spring means normally throwing the contact arm to open position with respect to its contact, an armature pivoted upon the base on an axis common to the axis of the switch arm, said armature being connected to the switch arm for movement therewith, an electromagnetic coil mounted upon the base on an axis substantially parallel to the base, a holding coil for said armature mounted upon the base on an axis close to and non-perpendicular to the base and in armature attracting opposition with respect to the coil first mentioned, and a normally closed auxiliary contactor switch assemblage comprising contacts mounted upon the armature and holding coil.

3. In an accelerating contactor the combination of an insulation panel, a circuit controlling switch including a contact mounted upon the panel and a switch arm pivoted upon the panel on an axis close to and parallel to the plane of the panel, an armature connected to the switch arm for movement therewith, an electromagnetic coil mounted upon the panel on an axis parallel to the plane thereof for said armature, means normally holding the switch arm open with respect to its contact and with the armature spaced from said coil, a holding coil assemblage mounted upon said panel with the holding coil axis in non-perpendicular relation with respect to the panel, said holding coil working in opposition upon said armature with respect to the first mentioned coil and having an air gap adjusting core, auxiliary contact means carried by said holding coil assemblage, and means carried by said

armature for closing a circuit thru the auxiliary contact means when the switch arm is open.

4. In a contactor for the control of electric circuits the combination of a supporting base, a main circuit controlling switch comprising a contact mounted upon the base and a movable contact arm mounted upon the base, an armature connected to said switch arm for movement therewith, an electromagnetic coil mounted upon said base for attraction of the armature to close the switch upon its contact, means normally holding said switch open, a circuit holding coil mounted upon the base having a core in complementary association with said armature but operating in opposition therewith with respect to the electromagnetic coil first mentioned, and a switch mounted upon said armature and holding coil in normally closed position when the main circuit switch is open.

5. In a circuit controlling contactor the combination of a shallow insulating supporting panel, an L-shaped rocker arm structure, means mounting the rocker arm structure upon a definite pivot axis upon and close to the panel, said rocker arm structure including a switch arm extending substantially parallel to the plane of the panel, a contact at the movable end of the switch arm, a contact mounted upon the panel for the contact of said switch arm, said rocker arm structure having an outstanding armature providing portion transversely disposed with respect to the switch arm and the plane of the panel, and magnetic coils mounted upon said panel with their axes non-perpendicular to the panel and in axial lines close to the plane of the panel at opposite sides of said armature for selective attraction of the armature by said coils.

6. A contactor as claimed in claim 5 having an auxiliary contactor assembly including contact means carried by one of said coils and contact means carried by said armature in position to close a circuit when the said armature is in attracted position by said last mentioned coil.

7. In a circuit controlling contactor the combination of a shallow insulating supporting panel, a magnetic coil mounted upon said panel with its axis parallel and close to the plane of the panel, a rocker arm structure pivoted upon a definite pivot axis close to the panel including a switch arm lying substantially parallel to the panel and

5

10

15

20

25

30

having also an outstanding armature portion arranged in a plane transverse to the plane of the panel and in position to be attracted by the magnetic coil aforesaid, a holding coil, means mounting the holding coil upon the panel with its axis close to and in acute angled relation with respect to the plane of the panel at the opposite side of the armature with respect to the first mentioned coil and having a contact face arranged to hold the armature in a plane at right angles to the axis of the holding coil when the latter has attracted said armature.

8. In an accelerating contactor the combination of a shallow insulation panel, a main line switch including a stationary contact mounted upon the panel, a switch arm pivoted upon the panel on an axis close to and parallel to the plane of the panel, a contact on the switch arm for engagement with the contact first mentioned, an electromagnetic coil mounted upon the panel on substantially a parallel axis with respect to the plane of the panel, an armature connected to and movable with the switch arm for said electromagnet, a holding coil mounted upon said panel on an axis close to and non perpendicular to the panel at the opposite side of the armature with respect to said electromagnetic coil, and an auxiliary contact assembly including spring actuated contact means carried by said armature and a complementary contact means carried by said holding coil in position to be engaged by the armature auxiliary contact means when the holding coil is attracting said armature.
